UNITED STATES PATENT OFFICE.

ROBERT G. TAYLOR, OF CHICAGO, ILLINOIS.

ADJUSTABLE TABLE-TOP COVER.

1,219,790.

Specification of Letters Patent. Patented Mar. 20, 1917.

Application filed March 1, 1916. Serial No. 81,439.

To all whom it may concern:

Be it known that I, ROBERT GRAY TAYLOR, a citizen of the United States, residing at Chicago, in the county of Cook and State of Illinois, have invented certain new and useful Improvements in Adjustable Table-Top Covers, of which the following is a specification.

This invention relates to covers for table tops and has as its object to provide a cover which may be readily and quickly applied to and removed from the tops of dining and similar tables and which will effectually protect the finish of the tops while the tables are being moved from place to place or being shipped, and it is one aim of the invention to so construct the cover that it may be applied to table tops of various sizes and readily adjusted so as to effectually protect the top both as concerns the upper surface thereof and also the rail or edge of the top.

Another aim of the invention is to provide a table top cover of the class described embodying a draw string whereby the cover may be tightened or drawn about the table top after application thereto and to provide a novel hem arrangement for housing the said draw string.

Another aim of the invention is to so arrange the draw string that the same may be drawn very tight without likelihood of tearing the hem within which it is housed.

Another aim of the invention is to so construct the cover that the same will present a soft and smooth surface to the table top and to provide the cover with a lining so built up as to effectually prevent mar-ring of the top without rendering the cover so thick as to be bunglesome.

40 In the accompanying drawings:

Figure 1 is a perspective view of the cover applied to a table top.

Fig. 2 is a bottom plan view of a portion of the cover removed from the table top.

45 Fig. 3 is a detail sectional view through the marginal portion of the cover removed.

Fig. 4 is a fragmentary perspective sectional view of the reverse side of a portion of the cover, the hem being opened to illustrate the construction and arrangement thereof.

The table top cover embodying the present invention is preferably made up from three thicknesses of material, the upper or outer

thickness or ply being indicated by the numeral 1 and being of heavy drill or duck, the intermediate ply or thickness being indicated by the numeral 2 and being preferably of heavy felt, and the under or inner ply or thickness being indicated by the numeral 3 and being of heavy canton flannel, this latter thickness being so arranged that its nap surface or side will be presented to the table top when the cover is applied to the top. The several thicknesses or plies are united to each other by lines of stitching indicated at 4 and these lines of stitching are preferably arranged in two series extending parallel to each other and the lines of stitching of the two series intersect each other and preferably at right angles, as clearly shown in Fig. 1 of the drawings. By thus uniting the plies or thicknesses of material comprising the cover the several thicknesses are prevented from becoming 55 relatively displaced or from becoming bulged. The several thicknesses are also united by a line of stitching 5 extending concentric to the margin of the cover and intersecting all of the lines of stitching 4 60 as will be apparent by reference to Fig. 4 65 of the drawings. 70

The thickness 1 projects at its marginal portion beyond the margins of the thicknesses 2 and 3 as clearly shown in Fig. 3 of 75 the drawings so as to provide one side 6 of the hem in which the draw string above referred to is housed. A suitable piece of material 7, which may be of the same kind as the thickness 1, is united by the line of 80 stitching 5 at its inner marginal portion to the first mentioned thicknesses and with its said inner marginal portion lying immediately below the margin of the thickness 3. The outer edges of the portions 6 and 7 are 85 turned in and united by a line of stitching 8 which serves to close the hem, this hem being indicated specifically by the numeral 9. By reference to Fig. 4 of the drawings it will be observed that the lines of stitching 4 extend beyond the line of stitching 5 and serve to unite the portion 6 of the thickness 1 to the outer marginal portions of the thicknesses 2 and 3 but that the lines of stitching 4 do not pass through the portion 7 so that 90 beyond the line of stitching 5 the portion 7 is wholly disconnected from the marginal portions of the thicknesses 2 and 3. The 95 100 105

draw string is indicated by the numeral 10 and is arranged within the hem 9 and has its end portions led outwardly through a single eyelet 11 secured within an opening in 5 the portion 7 of the said hem.

It will now be understood that in applying the cover to a table top the cover is spread over the top and the ends of the draw strings 10 are then drawn through the eyelets 11 and are tied. By leading the ends of the draw string through a single eyelet the said ends may be drawn tightly without likelihood of the portion 7 of the cover being torn which, however, would probably occur if the draw string were led through 15 two eyelets arranged in spaced relation with respect to each other. It will also be understood that the cover may be applied to table tops of various diameters and to tops supported upon pedestals of various sizes and that when applied to a table having a relatively large pedestal the marginal portion of the cover may be drawn tightly about the pedestal with the draw string lying between 20 the portion 7 and the under ply 3.

Having thus described the invention, what is claimed as new is:

1. A cover for table tops and the like comprising a body portion having an inner ply 30 provided with a soft nap surface to contact the surface of the table, an outer ply of heavy material, an intermediate ply, the said body portion having a marginal hem one side of which is formed by the marginal portion of the outer ply, the marginal portions of the inner and intermediate plies extending within the hem and all of the said plies being united adjacent their margins by a line of stitching extending in 35 spaced relation to their outer edges and by lines of stitching radiating from the first mentioned line of stitching, and a piece of material secured at its outer marginal portion to the margin of the outer ply and at 40

its inner marginal portion secured by the 45 first mentioned line of stitching.

2. A cover for table tops and the like comprising a body portion having an inner ply provided with a soft nap surface to contact the surface of the table, an outer ply of 50 heavy material, an intermediate ply, the said body portion having a marginal hem one side of which is formed by the marginal portion of the outer ply, the marginal portions of the inner and intermediate plies extending within the hem and all of the said plies being united adjacent their margins by a line of stitching extending in spaced relation to their outer edges and by lines of stitching radiating from the first mentioned 55 line of stitching, and a piece of material secured at its outer marginal portion to the margin of the outer ply and at its inner marginal portion secured by the first mentioned line of stitching, all of the said plies being 60 united throughout the intermediate or body portion of the cover by intersecting lines of stitching.

3. A cover for table tops and the like comprising a body portion consisting of an inner 70 ply, an outer ply, and an intermediate ply, the said body portion having a marginal hem, one side of which is formed by the marginal body of one of the plies, the marginal portions of the other plies extending within 75 the hem and all of said plies being united adjacent their margins by a line of stitching extending in spaced relation to their outer edges and by lines of stitching extending from the first-mentioned line of stitching, and a piece of material secured at its outer marginal portion to the margin of the first-mentioned ply and at its inner marginal portion secured by the first-mentioned 80 line of stitching.

In testimony whereof I affix my signature.

ROBERT G. TAYLOR. [L.S.]
